CLAIM

The ornamental design for a layer of a transaction card, as shown and described.

DESCRIPTION

FIG. 1 is a front isometric view of a layer of a transaction card according to a first exemplary embodiment of the present invention;

FIG. 2 is a front elevation view thereof;

FIG. 3 is a rear elevation view thereof;

FIG. 4 is an elevation view thereof taken from the left side;

FIG. 5 is an elevation view thereof taken from the right side;

FIG. 6 is a top plan view thereof;

FIG. 7 is a bottom plan view thereof; and

FIG. 8 is an enlarged view of a portion of FIG. 4.

FIG. 9 is a front isometric view of a layer of a transaction card according to a second exemplary embodiment of the present invention;

FIG. 10 is a front elevation view thereof;

FIG. 11 is a rear elevation view thereof;

FIG. 12 is an elevation view thereof taken from the left side;

FIG. 13 is an elevation view thereof taken from the right side;

FIG. 14 is a top plan view thereof;

FIG. 15 is a bottom plan view thereof; and,

FIG. 16 is an enlarged view of a portion of FIG. 12.

The broken line showing of the layer of the transaction card is for the purpose of illustrating portions of the layer of the transaction card and forms no part of the claimed design.
